(57) **CLAIM**

The ornamental design for an airbag shield, as shown and described.

DESCRIPTION

FIG. 1 is a front perspective view of the airbag shield showing our new design;

FIG. 2 is a front view thereof;

FIG. 3 is a back view thereof;

FIG. 4 is a top view thereof;

FIG. 5 is a bottom view thereof;

FIG. 6 is a left end view thereof; and,

FIG. 7 is a right end view thereof.

The portions showing broken lines are not part of the claimed invention, but are included to show environment.
